UNITED STATES PATENT OFFICE.

WILLIAM G. SLAUSON, OF PAINESVILLE, OHIO, AND WALTER W. MACFARREN, OF PITTSBURGH, PENNSYLVANIA; SAID MACFARREN ASSIGNOR TO SAID SLAUSON.

ROTARY ASSEMBLING-MACHINE.

1,202,908.

Specification of Letters Patent. Patented Oct. 31, 1916.

Application filed January 31, 1911. Serial No. 605,804.

To all whom it may concern:

Be it known that we, WILLIAM G. SLAUSON and WALTER W. MACFARREN, citizens of the United States, residing, respectively, at 5 Painesville, Lake county, Ohio, and Pittsburgh, Allegheny county, Pennsylvania, have invented certain new and useful Improvements in Rotary Assembling-Machines, of which the following is a specification.

10 Our invention relates to gathering or stuffing machines for use in making books, pamphlets, etc., or in assembling the several sections of a Sunday newspaper.

Broadly speaking, our invention consists 15 of a series of holders each containing one of the sections to be assembled, a means for discharging one of the sections from each holder in timed relation to the other, means for delivering said section to a conveyer operating in timed relation to the aforesaid means, and in means for opening one or 20 more folded sections and placing them around the other sections to form a cover.

A prime object of our invention especially 25 for newspaper work is to provide mechanism which will accomplish the above results at high speed, as with modern printing presses the various sections are delivered at the rate of many thousand per hour. Our improved 30 machine will therefore assemble and deliver several hundred complete bundles per minute.

To these ends our invention comprises the various devices hereinafter described and 35 illustrated in the accompanying drawings in which—

Figure 1 is a diagrammatic plan view of the complete machine. Fig. 2 is a diagrammatic elevation of the conveyer and delivery 40 rollers. Fig. 3 is a plan view of a part of a portion of the receiving saddle. Fig. 4 is an enlarged cross section through the machine. Fig. 5 is a diagrammatic view similar to Fig. 4 of a modification thereof. Fig. 45 6 is a longitudinal section through one of the rotary suckers. Fig. 7 is a diagram showing a bundle of gathered sheets on the conveyer. Fig. 8 is a similar diagram showing a cover dropping over the gathered 50 sheets.

The machine consists of a series of chutes 1 containing the sheets 2 standing on a folded edge therein. The chutes 1 may be provided with a plain bottom of any desired material, the smoother the better, but

the preferred construction is shown in Fig. 4 in which the bottom of the chute comprises the endless belt 3 mounted on the pulleys 4 and 5 having the intermediate supporting roller 6. The pulley 4 is mounted on a 60 shaft 7 which also carries a small brake drum 8. A brake shoe 9 is fastened to a lever 10 which is pivoted on the pin 11. A weight 12 adjustably mounted on the lever 10 serves to vary the braking effect. At 65 the lower end of the pile of sheets 2 there is mounted a rotary sucker 13, a rotary sucker 14 and a gripping roller 15. Between the suckers 13 and 14 there is placed a shaft 16 carrying several pulleys 17 and a gear 18. 70 The gear 18 drives teeth 19 upon the suckers 13 and 14. The gripping roller 15 is driven by the gear teeth 20 upon the sucker 14. A third sucker 21 is placed adjacent to the sucker 14 and driven thereby. The 75 shafts 22 and 23 are provided with several pulleys 24 and 25 respectively; these pulleys being in the same vertical planes as the pulleys 17, and the grooves 26 in the suckers 14 and 21. Small belts or tapes 27 run over the pulleys 17 and 24 and the sucker 14 and similar tapes 28 run over the pulleys 25 and the sucker 21. A stationary guide or "saddle" 29 made preferably of thin sheet metal is supported by the standards 30 secured to the 80 frame 31 of the machine. The upper edge of the saddle 29 is serrated as shown in Fig. 2; one of these serrations is opposite each sucker 21. Below each leg of the saddle 29 there is placed a conveyer chain 52 having 85 V-shaped flights 53 closely spaced. The chains 52 run on sprockets 32 the same being mounted on a shaft 33. Similar sprockets are provided at the other end of the machine. Power to drive the suckers, 13—14 and 21 is 90 applied to shaft 16; shaft 16 is driven by a sprocket chain 34 receiving power from a sprocket 35 upon a shaft 36, which is in turn driven by beveled gears 37 and 38 the latter being mounted upon the shaft 33; 39 is a 95 pulley to which power may be applied to drive the whole machine. The sucker 13 operates merely to strip the sheets 2 off the pile, while the sucker 14 assists in this operation and also carries the paper around approximately a half circumference and delivers it between itself and sucker 21. 100

All the suckers are of similar construction, the difference being in the amount of angular travel during which the suction ef- 110

fect is operated. All the suckers consist of a shell 40 mounted on annular bearings 41 the latter being supported by tubular members 42 secured to the frame 31. Sucker 14 is provided with a stationary valve 43 mounted on a tube 44; the tube 44 is mounted on sliding guides 45 controlled by the springs 46, which act to keep the valve 43 in close contact with the bore of the shell 40. The valve 43 is provided with a port 47 communicating with the interior of the tube 44 through which a partial vacuum may be created by any desired means. Small ports 48 are cut in the shell 40. The 15 ports 48 may be called sucker ports and the port 47 the suction port, and there being a partial vacuum maintained constantly in port 47, there will be a partial vacuum created in each of the ports 48 as they come 20 into communication with the port 47 which will be broken when the port 48 reaches the relief port 49. In sucker 13 the port 47 is merely wide enough to cover two of the sucker ports 48; in this way the moving 25 force of the sucker 13 is confined to a direction tangent to its circumference. The sucker ports 48 cover about one fourth of the shell 40, this being sufficient to move the paper until it is engaged by other 30 means. In sucker 14 however the sucker ports 48 extend about half way around the circumference and the port 50 in the valve 51 is correspondingly wider the suction effect being maintained for about a half revolution. 35 In sucker 21 the valve 52 may be a duplicate of the valve 43. The suckers 13 and 14 together strip the sheet off the end of the pile; after it moves a slight amount it is gripped between the sucker 14 and the gripping 40 roller 15 and carried around between the suckers 14 and 21. If it is merely desired to gather the papers as shown in Fig. 7 the sucker 21 may be made inoperative by cutting off the suction thereto in which case 45 the papers would be delivered between the tape 27 and the saddle 29, and would fall on the flights 53. In case however, it is desired to put a cover over the pile of sections as shown at 54, in Fig. 8 the sucker 50 21 is made operative and it draws one edge of the folded sheet toward itself, the other edge being drawn toward the sucker 14 which results in the cover being delivered astraddle of the saddle 29 and any gathered 55 sections thereon, the downcoming edges being guided by the tapes 27 and 28. In case it is desired to have each section except the first inclose all the previous sections, so that all the sections except the first 60 are in effect covers, all the suckers may be operated to produce this result and each delivered bundle would be a combination of inserts. The dotted rectangle 54^a represents a completed bundle just about to be discharged from the machine.

If the cover 54 is a single sheet containing a single fold the above action will be perfectly accomplished, but if the cover 54 is a sheet containing two folds as is usually the case with the cover section for a newspaper, it will be seen that the suckers 14 and 21 can act directly only on the outside thickness of paper at the end of the cover containing the loose edges; the end of the cover containing the folded edge will open 70 with certainty but the end of the cover having the loose edges may not do so. For this reason the saddle 29 has been serrated as shown in Fig. 2, the high points 55 of the saddle corresponding to the folded edge of 75 the cover and the low portions 56 to the loose edge of the cover this giving the loose edges of the cover more time to open.

In addition to the above, we provide nozzles 57 supplied by an air pipe 58 for blowing a jet of air between the folded edges of the cover as they are delivered from between the suckers 14 and 21, to insure the complete separation of the inner sheets of the cover. 90

The assembled papers are delivered off the left end of the saddle 29 as shown in Fig. 1 and passed between a pair of guides 59 which lead into the delivery rollers 60, which deliver them into any suitable receptacle. 95

The gearing connecting the shaft 16 and the shaft 33 is such that the conveyer chains 52 move an amount equal to the distance from center to center of chutes 1 for each 100 revolution of the suckers so that in passing a series of chutes one paper from each chute will be delivered at the same point on the conveyer chains 52 to form an assembled pile. 105

In Fig. 5 we have shown a modification of the arrangement shown in Fig. 4 in which separate stripping suckers 61 are provided to strip the sheet off the pile; these suckers would be duplicates of sucker 13. 110 A pair of gripping rollers 62 engages the sheet after it is moved a couple of inches and pushes the same through the curved guide 63 which delivers the edge of the sheet between a pair of opening suckers 64 115 which may be duplicates of sucker 21. The saddle 29 and the tapes 27 and 28 may be the same as previously shown. In the arrangement shown in Fig. 5 four suckers are required to do the work of the three shown 120 in Fig. 4 but in many cases this arrangement might have practical advantages as the relation between the lower end of the pile of papers and the saddle 29 can be varied greatly to suit the conditions of 125 service.

From the above it will be seen that we have provided simple and efficient mechanism for the purpose described, the details of which may be widely varied from those 130

shown without departing from the spirit of our invention as covered by the following claims.

We claim—

5. 1. A machine for assembling newspapers or the like comprising an inclined chute for holding a pile of sheets, a plurality of continuously rotating suckers in contact with the end sheet of the pile and rotating in the same direction at the same speed, and provided with a series of longitudinal ports in the circumference of each of said suckers and parallel to the axes thereof, in combination with means for opening a folded sheet.
10. 2. A machine for assembling newspapers or the like comprising an inclined chute for holding a pile of sheets, a plurality of rotary suckers in contact with the end sheet of the pile and rotating in the same direction at the same speed, each of said suckers having an internal stationary valve, a gear on each of said suckers, and a gear in driving connection with both of said gears on said suckers in combination with means for opening a folded sheet.
15. 3. A machine for assembling newspapers or the like comprising an inclined chute for holding a pile of sheets, a plurality of rotary suckers in contact with the end sheet of the pile and rotating in the same direction at the same speed, a valve in the lower sucker having a narrow port confining the suction effect practically to the plane of the sheet, and a valve in the upper sucker having a comparatively wide port whereby the upper edge of the sheet is carried part way around the sucker before being released in combination with means for opening a folded sheet.
20. 4. A machine for assembling newspapers or the like comprising an inclined chute for holding a pile of sheets, a continuously rotating sucker at the lower end of the pile and in contact with the end sheet thereof, a valve in said sucker controlling the suction and a conveyer to which the said sucker delivers the sheets in combination with means for opening a folded sheet.
25. 5. A machine for assembling newspapers or the like comprising an inclined chute for holding a pile of sheets, a bottom for said chute comprising an endless belt mounted on freely moving rollers whereby the sheets may be moved down the inclined chute by gravity, a continuously rotating sucker in contact with the upper edge of the sheet at the lower end of the pile, and a positively driven roller in contact with said sucker whereby the sheet will be gripped between the sucker and the roller in combination with means for opening a folded sheet.
30. 6. A machine for assembling newspapers or the like comprising a support for a pile of folded sheets, a pair of parallel rotary suckers, the first sucker being in contact with the end sheet of the pile to engage the end
35. sheet, and means for rotating the pair of suckers so that their adjacent surfaces run together, whereby the first sucker will engage one fold of the sheet, move the sheet off the pile and deliver the other fold to the second sucker after which each sucker pulls one fold of the sheet away from the other fold to cause a separation between the folds.
40. 7. A machine for assembling newspapers or the like comprising a series of sheet holders each provided with means for opening a folded sheet of paper comprising two parallel rotary suckers close together and running with their upper surfaces approaching each other, means for delivering the unfolded edges of a folded sheet between said suckers, whereby each of said suckers engages one of said folds and carries it away from the opposite fold, and a conveyer operating below said suckers having upwardly extending flights over which said opened sheet may fall with a fold on each side of said flights, means for driving said suckers and mechanism connected with said driving means for operating said conveyer at a fixed speed relative to the speed of said suckers.
45. 8. A machine for assembling newspapers or the like comprising a pair of oppositely rotating suckers close together, means for presenting between the suckers the unfolded edges of a sheet, a set of idler pulleys below each of said suckers and a set of tapes passing over each of said suckers and over one of said sets of idler pulleys for limiting the opening of the sheet.
50. 9. A machine for assembling newspapers or the like comprising a pair of oppositely rotating suckers geared together and on the same level, means for presenting between the suckers, the unfolded edges of a sheet, a set idler pulleys below and to the left of the right hand sucker, a second set of idler pulleys below and to the right of the right hand sucker, a set of tapes passing over the right hand sucker and the right hand idlers, and a second set of tapes passing over the left hand sucker and idlers, whereby the opening between the folds is limited by the tapes and the sheet is assisted in its downward travel by frictional contact with the tapes.
55. 10. A machine for assembling newspapers or the like comprising a pair of rotary suckers close together for opening a folded sheet, means for delivering said sheet to said suckers, an inverted V-shaped support directly under said suckers, and a conveyer under each leg of the support for removing the sheets therefrom.
60. 11. A machine for assembling newspapers or the like comprising a pair of rotary suckers close together for opening a folded sheet, means for delivering said sheet to said suckers, an inverted V-shaped support directly under said suckers, a conveyer chain under each leg of the support, and V-shaped flights

thereon to support an edge of the sheet, said conveyer operating parallel to said support.

12. A machine for assembling newspapers or the like comprising a series of inclined chutes for holding a pile of sheets, a continuously rotating sucker in contact with the end sheet of each pile for stripping the sheets off the pile, means for delivering the 10 sheets downwardly, a stationary saddle having inclined sides against which the sheets may lean and a conveyer below said saddle to receive and carry the sheets by their lower edges, said conveyer being operated in timed 15 relation to said suckers, whereby each bundle of sheets delivered by said conveyer will contain a sheet from each of the chutes.
13. A machine for assembling newspapers or the like comprising a series of inclined 20 chutes for holding piles of sheets, a continuously rotating sucker in contact with the end sheet of each pile for stripping the sheets off the pile, a conveyer operating past said chutes, means for dropping said sheets 25 on said conveyer, and a pair of oppositely rotating suckers at certain of said chutes arranged to open a folded sheet and to drop the same over a bundle of sheets taken up by the conveyer from the preceding chutes, to 30 form a cover therefor.

14. A machine for assembling newspapers or the like comprising a series of inclined chutes for holding piles of sheets, a continuously rotating sucker in contact with the 35 end sheet of each pile for stripping the sheets off the pile, a saddle, a conveyer beneath the same, means for dropping single sheets simultaneously upon the conveyer from several of the chutes, said sheets leaning against either side of the saddle and oppositely rotating suckers at certain of the chutes located above said saddle for opening a folded sheet whereby it straddles the saddle and any gathered sheets thereon to form 45 a cover for said sheets.

15. A machine for assembling newspapers or the like comprising a series of sheet holders, a continuously rotating sucker at each of said holders for withdrawing the sheets and 50 discharging them at alined points, means at some of said holders for opening the sheets as discharged, a conveyer for removing the gathered sheets, and a pair of rollers on vertical axes at the delivery end of the conveyer 55 between which the completed bundle is passed.

16. A machine for assembling newspapers

or the like comprising an inclined chute for holding a pile of folded sheets, a movable belt forming a bottom therefor, a rotary 60 sucker for successively stripping the sheets off the end of the pile and discharging them with the unfolded edges down, means for opening the fold, and guiding means above and below said sucker for guiding the sheets. 65

17. A machine for assembling newspapers or the like comprising an inclined chute for holding a pile of folded sheets, a movable belt forming a bottom therefor, a rotary sucker for successively stripping the sheets 70 off the end of the pile and discharging them with the unfolded edges down, means for opening the fold, guiding means above and below said sucker for guiding the sheets and a friction brake connected to said belt for 75 controlling the feed of the pile.

18. A machine for assembling newspapers or the like comprising a series of sheet holders, means at each of said holders for stripping the sheets off the pile, means for separately discharging the sheets at alined points of delivery, a stationary guide having a section like an inverted letter V, a conveying chain under each of the lower points of the V adapted to support the lower edges of the 85 sheet and means for driving said chains in timed relation to the means for discharging the sheets.

19. A machine for assembling newspapers or the like comprising a series of sheet-hold- 90 ers, means at each of said holders for stripping the sheets off the pile, means for separately discharging the sheets, means at some of said holders for opening the sheets as discharged; a stationary guide over which 95 the opened sheets fall and against which the unopened sheets lean, a conveyer under said guide for moving the sheets along the guide and means for closing in the folds of the outer sheet about the inner sheets.

20. A machine for assembling newspapers or the like comprising a series of sheet hold- 100 ers, means for withdrawing the sheets and discharging them at alined points, and a conveyer operating continuously under said 105 points to receive the sheets, said conveyer being provided with flights for supporting the edges of the sheets.
